ATTORNEY

UNITED STATES PATENT OFFICE

SAMUEL KRAMER, OF NEW YORK, N. Y.

DESIGN FOR A LIGHT FIXTURE

Application filed November 16, 1929. Serial No. 33,471. Term of patent 3½ years.

To all whom it may concern.

Be it known that I, SAMUEL KRAMER, a citizen of the United States, and resident of New York city, New York, have invented a certain new, original, and ornamental Design for a Light Fixture, of which the following is a specification, reference being had to the accompanying drawing, forming part thereof, in which,

Fig. 1 is a front view of the fixture, and Fig. 2 is a partial plan view of the same.

I claim:

The ornamental design for a light fixture substantially as shown.

SAMUEL KRAMER.
